UNITED STATES PATENT OFFICE

2,014,217

ELECTRIC SWITCH ACTUATING
MECHANISM

William Williamson, Valley Stream, N. Y.

Application November 8, 1934, Serial No. 752,049

4 Claims. (Cl. 240—123)

This invention relates to improvements in electric switch operating mechanisms.

One of the several objects of the invention resides in an operating mechanism for electric switches of the pull chain type which imparts an even pull upon the pull chain to "on" and "off" positions irrespective of the manual force applied to actuate the same, thus eliminating the possibility of breaking the pull chain due to excessive force, and the danger of upsetting a table lamp or other unstable electric device with which the switch may be associated.

Another feature of the invention is to provide a turnable actuating mechanism for electric pull chain switches which is more easily grasped for imparting a pull upon the pull chain than the annoyance of reaching for the pull chain for actuation direct, and which is also more easily accessible in the dark or dimly lighted room.

A further object of the invention is the provision of an electric pull switch actuating mechanism which is especially adapted for use upon tables or floor lamps, and which lends attractiveness thereto so as not to detract from the decorative or artistic appearance of the lamp.

A still further object is the provision of an electric pull switch actuating mechanism which is simple and inexpensive of manufacture, and of such novel construction as to assure positive operation on each actuation thereof.

With these and other objects in view, the invention resides in the certain novel construction, combination and arrangement of parts, the essential features of which are hereinafter fully described, are particularly pointed out in the appended claims, and are illustrated in the accompanying drawing, in which:

Figure 1 is a front elevational view of a table lamp illustrating my invention in use thereon.

Figure 2 is a side elevational view with the electric lamp and shade removed.

Figure 3 is a vertical transverse sectional view on the line 3—3 of Figure 2, but showing in dotted lines the position of the actuating mechanism when exerting a pull upon the pull chain.

Figure 4 is an enlarged vertical transverse sectional view on the line 4—4 of Figure 1.

Referring to the drawing by reference characters, the numeral 10 designates the base of an electric lamp of the table type, from which a pedestal or standard 11 rises, the top of the pedestal supporting an electric lamp socket switch 12 of conventional construction, and which includes a flexible pull chain 13 by which the switch

mechanism may be actuated to "on" and "off" positions. The electric lamp socket switch 12 receives the conventional electric lamp 14, the light from which is shielded by a lamp shade 15.

Rotatably mounted upon a screw 16 which is threaded transversely into the pedestal 11 is a rotatable manipulating member 17, which in the present instance is shown in the shape of a ship's wheel, and includes a hub 18 through which the unthreaded portion of the screw 16 passes, radially extending spokes 19, and an annular felly 20 from which hand grips 21 radially extend. The shank of the screw 16 acts as a shaft on which the wheel 17 is rotatably mounted while the head of the screw 16 is countersunk within the hub 18 and is concealed by a cover plate 22 in which a luminous jewel 23 is mounted. This luminous jewel acts as a guide and facilitates the finding of the actuating member 17 in the dark.

Fixed to the inner side of the hub 18 by a screw 24 is an eccentric 25, the said eccentric having an eccentrically located opening 26 through which the screw 16 freely passes. The periphery of the eccentric disk 25 is grooved as at 27 and seated in the groove is an eccentric band 28 which is free relative to the walls of the groove. The eccentric band is seated in position by forming the eccentric disk 25 of two sections held together by the screw 24.

Extending outwardly from the eccentric band 28, is a pull chain connector 29 which is in the form of a radially extending post having a seat 30 in the outer end thereof for the reception of the lowermost bead of the beaded chain 13.

The beaded pull chain 13 is of such a length that when the eccentric 25 is at its uppermost position, the said chain contains a limited amount of slack, but as the eccentric turns in either direction, the pull is exerted upon the pull chain 13, taking up the slack, and as the eccentric reaches its lowermost position, the final pull is exerted upon the chain sufficient to actuate the switch mechanism within the switch socket 12 to either "on" or "off" position.

From the foregoing description, it will be seen that the manipulating member 17 in the form of a wheel may be manually grasped by an operator, and upon turning movement of the wheel the complete revolution, the switch may be turned from an "off" to an "on" position or vice versa. The eccentric 25 being fixedly connected to the rotatable actuating member moves therewith relative to the eccentric ring 28 and the said eccentric imparts the pull to the chain through the

eccentric ring as clearly shown in dotted lines in Figure 3 of the drawing.

By reason of the construction herein set forth an even pull may be exerted upon the pull chain of the lamp regardless of the force imparted to rotate the manipulating member 17, thus the possibility of breaking the pull chain is eliminated and furthermore, the actuating mechanism prevents the pull chain from snapping upward and becoming entangled or twisted with the lamp support or lamp shade. The actuating mechanism herein set forth also reduces the danger of upsetting the lamp which sometimes occurs when the pull chain is directly actuated.

15 While I have shown and described what I consider to be the most practical embodiment of my invention, I wish it to be understood that such changes as come within the scope of the appended claims may be resorted to if desired.

20 Having thus described the invention, what I claim as new and desire to secure by Letters Patent of the United States, is:—

1. In combination, an electric lamp having an electric lamp socket switch of the pull chain type, an eccentric to which the pull chain of said socket switch is connected, and rotative manipulating means for imparting a turning movement to said

eccentric for exerting a pull upon said pull chain to turn said socket switch "on" and "off".

2. In combination, an electric lamp having a pedestal and a pull chain switch socket at the top thereof, an actuating member rotatably supported upon said pedestal, and an eccentric fixed to said actuating member to which the free end of the pull chain is operatively connected.

3. An electric pull chain switch actuating mechanism comprising a shaft adapted to be fixed to a support, a manipulating wheel rotatably mounted on said shaft, an eccentric disk fixed to one side of said wheel and having an opening therein for the passage of said shaft, an eccentric band freely mounted upon the periphery of said eccentric disk, 15 and a pull chain connector carried by said eccentric band.

4. In combination, an electric lamp having a pedestal and a pull chain switch socket at the top thereof, a wheel rotatably mounted on said pedestal, an eccentric disk fixed to said wheel, an eccentric band on the periphery of said eccentric disk and free to move relative thereto, and a connector on said eccentric band to which the free end of the pull chain of said switch socket is connected.

WILLIAM WILLIAMSON.
